(57) **CLAIM**

The ornamental design for a wireless remote control, as shown and described.

DESCRIPTION

Fig. 1.1 is a front elevation view of a wireless remote control showing the new design in a first embodiment.

Fig. 8.1 is a front elevation view of a wireless remote control showing the new design in a second embodiment.

Fig. 13.1 is a front elevation view of a wireless remote control showing the new design in a third embodiment.

Fig. 19.1 is a front elevation view of a wireless remote control showing the new design in a fourth embodiment.

Fig. 25.1 is a front elevation view of a wireless remote control showing the new design in a fifth embodiment.

All the dark circular features shown on front of the remote control of the invention are coplanar with the major front surface.
